BOWLING PIN DOLL

Russell A. Pulcifer, 628 Oakdale St., Grand Rapids, Mich.

Filed Apr. 24, 1961, Ser. No. 64,881

Term of patent 14 years

(Cl. D34—4)

FIG. 1

FIG. 2

FIG. 4

FIG. 3

FIG. 1 is a perspective view of the bowling pin doll, showing my new design;

FIG. 2 is a side elevation view of the bowling pin doll illustrated in FIG. 1;

FIG. 3 is a reduced top plan view;

FIG. 4 is a sectional view taken on plane IV—IV of FIG. 2.

The stippled portion of the article is intended to indicate black or contrasting color.

I claim:

The ornamental design for a bowling pin doll, as shown and described.
